(No Model.)

H. A. BIERLEY.

HAND AND FOOT WARMER.

No. 350,342.

Patented Oct. 5, 1886.

UNITED STATES PATENT OFFICE.

HENRY A. BIERLEY, OF MANCHESTER, OHIO.

HAND AND FOOT WARMER.

SPECIFICATION forming part of Letters Patent No. 350,342, dated October 5, 1886.

Application filed October 24, 1885. Serial No. 180,849. (No model.)

To all whom it may concern:

Be it known that I, HENRY A. BIERLEY, a citizen of the United States, and a resident of Manchester, in the county of Adams and State of Ohio, have invented certain new and useful Improvements in Hand and Foot Warmers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved warming-pan. Fig. 2 is a similar view showing it used as a hand and foot warmer. Fig. 3 is a longitudinal vertical section of the same, and Fig. 4 is a transverse section.

Similar letters of reference indicate corresponding parts in all the figures.

My invention has relation to warming-pans; and it consists in the improved construction and combination of parts of a warming-pan which may be used as a hand and foot warmer, as a steam-table for keeping dishes hot when serving sick persons, as a drier for drying fluids which may have been spilled upon textile fabrics, and for any other purposes where it is desired to apply heat and to keep an object heated for a space of time, as hereinafter more fully described and claimed.

In the accompanying drawings, the letter A indicates an elliptical sheet-metal box or casing, having at its smallest diameter a flue or duct, B, closed at one end and provided with a sliding door, C, at its other end. This casing may be filled with hot water through one of two necks, D D, projecting from the top of the casing, and having perforated diaphragms E within them and caps F fitting upon them, said caps being preferably screw-caps fitting upon threads upon the necks, and a heated brick or block of metal may be placed into the flue or transverse chamber B, serving to keep the water hot. The casing is preferably provided at its top with a handle, G, for transporting it, and the top has two or more recesses or depressions, H, into which plates or dishes may rest without sliding to the sides. The threaded necks project usually upon the long axis of the casing, and threaded caps I, having upwardly-projecting tubes J, may fit

upon the threaded necks when the apparatus is used as a hand and foot warmer, and a bail-shaped tube, K, fits with its tubular legs upon the upwardly-projecting tubes, sliding upon the same. The perforated diaphragm within the necks D D prevents the water from being thrown up through and over the tops of the pipes J, and then passing out at the ends of K when subject to violent motion in a buggy or other vehicle in which it is being used.

When the apparatus is used as a hand and foot warmer, the casing is filled with hot water, a red-hot brick or block of metal is inserted into the transverse chamber, and the tubes and the bail-shaped tube is placed in position. The steam will now pass up through the upright tubes, so that by grasping the horizontal portion of the bail-shaped tube the hand may be warmed, and the said tube may be slid up or down upon the upright tubes, so that it may be within convenient reach for the person using it, who at the same time may keep his or her feet upon the casing and keep them warm.

When the apparatus is to be used as a common warming-pan, the upright tubes and the bail-shaped tube are removed, and the screw-caps are placed over the necks, when the pan may be placed into a bed to warm the same, or it may be placed over a damp spot or place where any fluid has been spilled, when it may dry it by the heat; or the pan may be used as a steam-table for the purpose of keeping plates hot, when plates or dishes may be placed into the recesses or depressions in the top of the casing and be prevented from sliding by resting in the recesses, while they at the same time are kept hot. The pan, being thus placed upon the bed with dishes upon it to serve as a table for an invalid, will, besides keeping the dishes warm, also keep the patient warm while moving to reach the several dishes, and thus prevent the patient from taking cold while he or she is moving, and thus unable to keep as well covered as when keeping perfectly still. When it is only desired to keep the pan heated for a short while, it is only used filled with hot water, without the heated brick or block of metal; but when it is desired to keep the pan warm for a considerable time the heated brick or block of iron is placed into its transverse chamber, where it will keep the water

hot, retaining the heat for a long time, and giving it off gradually to the water. In this manner a person may, while driving in very cold weather, have the pan placed in the bottom of the vehicle and keep his feet upon it, and when the hands get cold the bail-shaped tube may be grasped, and the said tube so adjusted that it will be within convenient reach, being either slid up or down.

Having thus described my invention, I claim and desire to secure by Letters Patent of the United States—

The combination, in a foot-warmer, of a

vessel for the reception of a warming medium, having two openings in its top, a neck secured in each opening, a tube secured in each neck, and a bail-shaped tube upon said two tubes, as shown and described.

In testimony that I claim the foregoing as my own I have hereunto affixed my signature in presence of two witnesses.

HENRY A. BIERLEY.

Witnesses:

LOUIS BAGGER,
AUGUST PETERSON.
